MOUNTING FOR ROCK DRILLS

Paul A. Lincoln, Bloomsbury, N. J., assignor to
 Ingersoll-Rand Company, New York, N. Y.,
 a corporation of New Jersey

Application March 27, 1943, Serial No. 480,727

3 Claims. (Cl. 255—51)

This invention relates to rock drilling mechanism, and more particularly to a mounting for rock drills of the hand-held type to enable such rock drill to be used as a drifter.

One object of the invention is to expedite the operations of attaching the rock drill to and releasing it from the mounting.

Another object is to avoid the need of special tools for connecting the mounting to the rock drill.

Still another object is to enable the mounting to be connected to the rock drill with a minimum of manual effort.

Other objects will be in part obvious and in part pointed out hereinafter.

In the drawing accompanying this specification and in which similar reference numerals refer to similar parts,

Figure 1 is a side view of rock drilling mechanism having the invention applied thereto,

Figure 2 is an end view of the rock drilling mechanism,

Figure 3 is a transverse view taken through Figure 1 on the line 3—3,

Figure 4 is a plan view taken through Figure 1 on the line 4—4, and

Figure 5 is a perspective view of a detail.

Referring more particularly to the drawing, 20 designates a rock drill, 21 a shell, and 22 a feed screw for actuating the rock drill 20 longitudinally of the shell 21 in order to maintain the rock drill in the correct driving relationship with a working implement (not shown) which it is intended to actuate.

The rock drill 20 is illustrated as being of the type that is intended to be held and guided by an operator during the drilling of a hole and accordingly has a lug or lugs 23 at its rearward end to accommodate a handle (not shown) whereby the rock drill may be gripped when used as a hand-held tool. In order to enable a rock drill of the latter type to be mounted upon the shell 21 so that it may be fed to and from the work by the feed screw 22, in the manner of a drifter, said rock drill is provided with a saddle 24 that is connected to the drill and threadedly connected to the feed screw so that the latter may be used to move the drill longitudinally of the shell 21.

The saddle 24 comprises a plate portion 25 having ribs 26 extending along its side edges to slide within grooves 27 in the inner surface of the shell 21. On the upper surface of the plate 25, near the front end thereof, are a pair of hooks 28 the inner surfaces 29 of which are shaped to conform with the contour of ears 30 on the casing 55

of the rock drill 20 that extend loosely into the hooks 28 for maintaining the intermediate and front portions of the rock drill in the correct operative position with respect to the shell.

5 At the opposite end of the plate 25 is a cross piece 31 having a groove 32 in its forward surface to receive the rearward sides of the lugs 23. The cross piece 31 is, moreover, provided in its end portions with apertures 33 that extend longitudinally of the saddle to receive, slidably, locking members 34 adapted to lock the lugs 23 to the cross piece.

The locking members 34 may be freely rotatable within the apertures 33 and are shown as 15 being in the form of hook bolts, the curved or hook portions 35 of which engage the forward surfaces 36 of the lugs 23 or, as shown, depressions 37 in the surfaces 36 to receive the ends of the hooks 35.

20 The locking members 34 are of such length that considerable portions thereof extend rearwardly of the cross piece 31, and on such rearwardly extending ends of the locking members are compression springs 38 that act against the lugs 23 25 and against nuts 39 on the members 34 for holding the hooks 35 normally in the depressions 37 and to hold the lugs 23 against the cross piece. The springs 38 are of suitable strength to hold the lugs 23 firmly seated in the groove 32 unaffected by the severe vibration to which the drilling mechanism is subjected during operation, and the force of the springs may be conveniently varied by adjusting the nuts 39 upon the locking members 34.

35 Owing to the heavy pressure of the springs 38 required to prevent vibration of the rock drill relatively to the cross piece 31, it would be difficult to apply sufficient pressure by manual force directly to the locking members 34 to cause them 40 to slide through the cross piece for disengaging the hooks 35 from the rock drill. It would, moreover, be inadvisable to unthread the nuts 39 for minimizing the pressure of the springs 38 each time it is intended to connect or disconnect the 45 saddle to or from the rock drill, since then much time would be consumed to so adjust the nuts 39 that each one of a number of springs 38 would be loaded in the same degree.

It is, accordingly, contemplated to use the force 50 that may be exerted by means of the feed screw 22, and its actuator, as for example a crank 40, for compressing the springs 38 and to cause relative sliding movement between the cross piece 31 and the locking members 34. To this end abutment means are placed in the path of movement

of the locking members 34 to engage them and hold them stationary when the saddle approaches its rearmost limiting position in the shell so that, upon further rearward movement of the saddle, the lugs 23 will move out of engagement with the hooks 35. The abutment means used for this purpose preferably consist of a pair of wings 41 that may be integral parts of the cross head 42 supporting the rearward end of the feed screw 22, said cross head 42 being, in turn, supported by rods 43 secured to the opposite sides of the shell 21, as is customary.

The free ends 44 of the wings 41 terminate in the longitudinal planes of the locking members 34 in such position that when the rearward end surfaces 45 of the locking members 34 engage the wings 41 the locking members 34 will be restrained against movement in a rearwardly direction.

The operation of the device is as follows: Whenever it is intended to place a rock drill 20 on the mounting the saddle 24 is first moved to a rearward position by means of the feed screw 22 to bring the ends 45 of the locking members 34 against the wings 41. Upon further movement of the saddle in a rearwardly direction the locking members will remain stationary and the space between the hooks 35 and the groove 32 will be enlarged sufficiently to permit the lugs 23 to be placed in the groove 32; it being assumed, of course, that the ears 30 have previously been placed in the hooks 28.

The feed screw 22 is then rotated in the opposite-hand direction to move the saddle 24 forwardly and thereby release the pressure of the cross piece 31 upon the springs 38. The springs

will then move the locking members to place the hooks 35 in engagement with the depressions 31 for locking the rearward end of the drill to the saddle.

5 I claim:

1. A mounting, comprising in combination with a rock drill and a shell, a saddle for the rock drill slideable in the shell, locking means to lock the rock drill to the saddle, and abutment means supported by the shell in a position to engage and release the locking means from the rock drill during a portion of the movement of the saddle in the shell.

15 2. A mounting, comprising in combination with a rock drill and a shell, a saddle for the rock drill having means to engage a portion of the rock drill and being slideable in the shell, locking means for locking another portion of the rock drill to the saddle and being slideable in the saddle, means for normally holding said locking means in locking position, and means supported by the shell positioned to engage and hold the locking means stationary during a portion of the movement of the saddle in the shell for releasing the rock drill from the locking means.

20 3. A mounting, comprising in combination with a rock drill and a shell, a saddle for the rock drill having means to engage a portion of the rock drill and being slideable in the shell, spring-30 pressed jaw means on the saddle to grip another portion of the rock drill, and a stationary member supported by the shell to abut and open said jaw means during a portion of the sliding movement of the cradle relatively to the shell for releasing the rock drill.

PAUL A. LINCOLN.
